UNITED STATES PATENT OFFICE.

FRANK W. CROW, OF CLARENCE, IOWA.

NON-REFILLABLE BOTTLE.

1,014,693.

Specification of Letters Patent. Patented Jan. 16, 1912.

Application filed May 12, 1911. Serial No. 626,769.

To all whom it may concern:

Be it known that I, FRANK W. CROW, a citizen of the United States, residing at Clarence, in the county of Cedar and State 5 of Iowa, have invented new and useful Improvements in Non-Refillable Bottles, of which the following is a specification.

The invention relates to bottle stoppers, and more particularly to the class of bottle 10 stoppers and anchoring mediums therefor.

The primary object of the invention is the provision of a stopper in which the same, when placed within the neck of a bottle, will be anchored therein, so that upon 15 the extraction of the stopper, it will fracture the anchoring means therefor, thus indicating that the bottle has been opened.

Another object of the invention is the provision of a stopper and an anchoring 20 medium therefor, whereby when the stopper has been once or originally inserted within the neck of the bottle, it will be held fast therein, so that upon the extraction of the 25 same from the bottle neck a person may detect that the bottle has been opened.

The invention consists generally in a cork or stopper in which is made fast a catch, which latter is adapted to engage with cross retaining wires disposed transversely within 30 the neck of a bottle, thereby anchoring the stopper therein, so that upon extracting said stopper from the neck, the retaining wires will be fractured for evidencing the removal of the cork from the bottle, thereby indicating 35 that the original contents has been tampered with.

With these and other objects in view, the invention consists in the construction, combination and arrangement of parts, as will 40 be hereinafter more fully described, illustrated in the accompanying drawings, and pointed out in the claims hereunto appended.

In the drawings: Figure 1 is a fragmentary vertical sectional view through a bottle, showing the cork or stopper therein, and the same anchored in accordance with the invention. Fig. 2 is a sectional view on the line 2—2 of Fig. 1. Fig. 3 is a perspective view of a stopper with its catch, showing a slight modification. Fig. 4 is a transverse sectional view through a bottle neck, showing a slight modification of the arrangement of the retaining wires.

55 Similar reference characters indicate cor-

responding parts throughout the several views of the drawings.

Referring to the drawings by numerals, 5 designates the neck portion of a bottle body of the ordinary construction, the same being preferably formed from glass, although the same may be formed from other suitable material, and within the neck 5 is inserted a stopper or cork 6, the same being formed with a disk like head 7 of a diameter corresponding to the diameter of the mouth edge of the neck, so that when the stopper or cork is inserted within the bottle neck, it will be impossible for a malicious person to insert a tool or other instrument 10 between the outer periphery of the cork and the inner wall of the neck for extracting the cork from the said neck, by spreading the catch for anchoring the cork therein, as will be presently described.

Spanning the bore in the neck 5 a distance spaced from the inner end of the stopper or cork 6, is a pair of retaining wires 8 constructed from metal or other fragile material, the same having their ends embedded 15 within the body of the bottle sufficiently secure, so as to prevent the pulling out of the wires therefrom when engaged by the catch carried by the stopper or cork, presently described.

Mounted securely within the inner end of the cork or stopper 6, and depending therefrom, is a pair of spring arms 9, the latter being provided with inturned upwardly directed bills or tines 10, which latter are adapted to engage and lock with the retaining wires 8 on the insertion of the stopper or cork 6 within the bottle neck 5. The tines 10 of the spring arms 9 are provided with beveled edges 11 which are 20 adapted to contact with the retaining wires 8, thereby spreading the arms 9 apart, when the cork or stopper 6 is being inserted within the bottle neck, so that the tines will lock with the retaining wires, thereby fastening 25 the stopper or cork within the bottle neck.

On the extraction of the cork or stopper 6, the tines 10 will exert a pull upon the retaining wires 8, causing the fracture or breaking thereof on the pulling of the cork or stopper from the bottle neck, thus evidencing the fact that the original seal of the bottle has been broken or that the cork or stopper has been extracted from the bottle neck, thereby enabling a person to detect 30

that the original contents of the bottle has been tampered with.

In Fig. 3 of the drawing, is shown a slight modification of the invention, wherein the 5 spring arms 12 are disposed at diametrically opposite points of the cork or stopper 13, contiguous to the outer periphery thereof, and are adapted to be brought into locked engagement with diagonally disposed retaining wires 14, shown in Fig. 4 of the drawing. These wires 14 have their ends embedded in the body of the bottle in a similar manner as the retaining wires 8, thereby holding the cork in the bottle neck when 10 once placed therein, but upon the extraction thereof, the wires will be fractured, indicating that the said cork or stopper has been removed from the bottle neck, thus permitting the detection of the fact that the original 15 contents has been tampered with.

It is, of course, understood that the retaining wires may be arranged in various different positions interiorly of the neck of the bottle, and also that the spring arms 20 may be differently constructed for locking engagement with the said retaining wires, for holding the cork within the bottle neck when once inserted therein, without depart-

ing from the spirit of the invention, as comes properly within the scope of the appended claims.

What is claimed is:

1. The combination with a bottle having a neck, of retaining wires arranged interiorly of the neck and held fast therein, and 30 a stopper insertible within the neck and having hook-like spring arms for locking engagement with the retaining wires, whereby the stopper will be held fast within the neck of the bottle.

2. The combination with a bottle neck having breakable retaining wires arranged interiorly thereof, of a stopper insertible within the neck, and means depending from the stopper and adapted for anchoring engagement with the retaining wires, whereby the stopper will be held fast within the neck and upon the extraction thereof will sever the said retaining wires.

In testimony whereof I affix my signature 40 in presence of two witnesses.

FRANK W. CROW.
